FEED WATER HEATER

Application filed January 31, 1930, Serial No. 425,017, and in France February 22, 1929.

The present invention relates to a device for heating the feed water of steam generators, and of locomotives in particular.

The apparatus according to the invention, 5 is characterized by the combination with a principal heater-condenser including a cold water inlet, a supply of steam under pressure and a warm water outlet, of a plurality of auxiliary condensers, the first of which communicates with the principal condenser from 10 which it receives the excess water and the non-condensed steam, while the second of said auxiliary condensers communicates with the first with the same object, and so on, 15 down to the final condenser which returns the excess water to the suction pipe of the cold water pump through a suitable duct, the last and if necessary each of said auxiliary condensers having a cold water inlet 20 whereby all the steam flowing from one condenser to the other may be progressively condensed, so that the last condenser is practically at atmospheric pressure without any loss of steam to the outside air.

25 The principal and auxiliary condensers have gas vents through which the gases and air given off by the warm water can make their way out. Said vents may be independent for each condenser, or may establish 30 communication between said condensers at their upper portions, the gas vent of the final condenser being always open to the atmosphere.

35 The principal and certain of the auxiliary condensers may be provided with safety valves, in particular the final condenser, in order to avoid any accidental excess pressure.

40 When the pressure prevailing in the principal condenser is higher than the exhaust steam pressure of the auxiliary engine which is likewise to be used for heating the water, said exhaust steam may be advantageously admitted directly into one of the auxiliary condensers in which the pressure is lower 45 than that of said exhaust steam.

Should it be desired to continue admitting said exhaust steam into the principal condenser, the pipe delivering said steam is fitted 50 with an automatic check valve which closes

when a predetermined pressure obtains within the principal condenser.

Other characteristics and peculiarities of the invention will be apparent from the ensuing description taken in conjunction with 55 the accompanying drawing which shows in sectional elevation a heater of the horizontal type embodying the improvements of the present invention.

The single figure of the drawing illustrates 60 diagrammatically one embodiment of the invention.

The heater illustrated comprises, as usual, a principal heater condenser 36 into which a sprayer 35 injects cold water discharged by 65 a pump 33 through the duct 34. Steam under pressure is likewise delivered through a duct 37 into said condenser 36, which steam by mixing with the cold water and condensing supplies warm water which is drawn off by 70 a warm water pump 41^a through a duct 41 to be discharged into the generator. The two pumps 33 and 41^a are driven from a single steam engine 30.

In accordance with the invention, a number 75 of auxiliary condensers 50, 51 (two in the case illustrated), are used in conjunction with the principal condenser 36. The auxiliary condenser 50 communicates with the principal condenser 36 through an orifice 52 the 80 level of which determines the upper limiting level of the warm water in the condenser 36. Similarly, an orifice 53 establishes communication between the two auxiliary condensers 50 and 51. To the last of these condensers is 85 fitted a duct 42 through which the excess water is returned to the suction pipe of the cold water pump.

Cold water is likewise injected in each of 90 the auxiliary condensers 50 and 51. To this end, a sprayer 57 or 58 fed through a cold water by-pass 59, is mounted in each condenser.

Each of the condensers, both principal and auxiliary, might have a gas vent formed near 95 the top and open to the surrounding air; in the case illustrated, the water is rid of its gas by causing the condensers to communicate with each other at their upper portions, for example, through orifices 54 and 55, and by 100

fitting to the last condenser a gas vent nozzle 56 open to the atmosphere.

The heater described above operates as follows:

5. The greater part of the steam admitted to the principal condenser 36 is condensed by the cold water and heats the latter. The non-condensed steam in addition to the excess warm water enters the first auxiliary condenser 50 through the orifice 52 where there is a further condensation of steam. The pressure in said condenser 50 is consequently much lower than that prevailing in the condenser 36. The non-condensed steam and the 10 warm water then pass out from this condenser 50 into the auxiliary condenser 51 in which a final condensation takes place, the pressure again falling and reaching atmospheric pressure approximately. The members 15 of the apparatus are so designed that the whole of the steam is condensed. As said condensation serves exclusively for heating the water which is drawn directly by the warm water pump or which is to return to the suction pipe of the cold water pump, the 20 efficiency of the apparatus is considerably higher than that of apparatus which are placed in communication with the atmosphere in order to balance the pressures.
25. The gases given off by the warm water and which pass from one chamber to another through the orifices 54 and 55, are finally withdrawn by the gas release nozzle 56. Safety valves 60 and 61 are mounted on the 30 principal condenser 36 and the auxiliary condenser 51 in order to avoid any accidental excess pressure.
35. In order to keep the last condenser at atmospheric pressure, the valve 61 may be combined with an air suction inlet valve. In 40 certain cases, it might be likewise advantageous to open the last condenser to the atmosphere. In view of the successive condensations, the loss of steam will be always 45 insignificant.
50. The steam entering the principal condenser 36 will be pressure steam derived from any suitable source. However, the invention is concerned in particular with the application to this heater apparatus of a method of taking steam, which consists in bleeding a certain quantity of live steam from the engine cylinder near the end of expansion within said cylinder.
55. Ordinary exhaust steam, and possibly the exhaust steam of the auxiliary engines arriving for example through a duct 62, might likewise be admitted to the principal condenser.
60. Preferably, an automatic check valve 63 will be inserted in said duct 62, said check valve closing said duct 62 when the pressure within the condenser 36 rises above the pressure of the exhaust steam of the auxiliary engines, in order to avoid said auxiliary en-

gines operating under back pressure. The duct 62 is then made to deliver directly into an auxiliary condenser in which the pressure is always lower than that of the steam of the auxiliary engine. To this end, a bypass tube 65 connected to the tube 62 to the front of the check valve 63 delivers the steam directly to the auxiliary condenser 50 through the valve 66.

In certain cases and as previously described, ejectors may be used to hasten the flow of water and steam from one condenser to another.

It is obvious that in all cases one or more pumps, and in particular the cold water pump could be replaced by an injector or the like.

I claim:

1. In a device for heating feed water, the combination with a principal heater-condenser including a cold water inlet, a steam inlet and a warm water outlet, of means for delivering cold water to said condenser, a plurality of intercommunicating auxiliary condensers, the first of which communicates with the principal condenser from which it receives the excess water and the non-condensed steam while the last returns the excess water to said cold water delivery means, each of said auxiliary condensers having a cold water inlet whereby the steam flowing from one condenser to another is progressively condensed so that the last condenser is practically at atmospheric pressure without any loss of steam to the outside air. 10
2. In a device for heating the feed water, the combination with a principal heater-condenser including a cold water inlet and a warm water outlet, of a pump for delivering cold water to said principal condenser, a plurality of intercommunicating auxiliary condensers, the first of which communicates with said principal condenser, means for delivering exhaust steam at a pressure lower than that prevailing in said principal condenser to the first of said auxiliary condensers in which the pressure is lower than that of said exhaust steam, and means for supplying cold water to each of said auxiliary condensers whereby the steam flowing from one condenser to another is progressively condensed; so that the last condenser is practically at atmospheric pressure without any loss of steam to the outside air. 11
3. In a device for heating feed water, the combination with a principal heater-condenser including a cold water inlet and a warm water outlet, of a pump for delivering cold water to said principal condenser, a plurality of intercommunicating auxiliary condensers, the first of which communicates with said principal condenser, means for delivering exhaust steam to said principal condenser, means including an automatic stop 12

valve for diverting said exhaust steam to the first of the auxiliary condensers in which the pressure is lower than that of said exhaust steam when the pressure prevailing in said 5 principal condenser is greater than that of said exhaust steam.
